UNITED STATES PATENT OFFICE.

LUTHER C. CROWELL, OF BROOKLYN, ASSIGNOR TO R. HOE & CO., OF NEW YORK, N. Y.

SHEET-SUPERIMPOSING MECHANISM.

SPECIFICATION forming part of Letters Patent No. 328,880, dated October 20, 1885.

Application filed February 25, 1884. Serial No. 121,925. (No model.)

To all whom it may concern:

Be it known that I, LUTHER C. CROWELL, a citizen of the United States, residing in the city of Brooklyn, county of Kings, and State 5 of New York, have invented certain new and useful Improvements in Sheet-Superimposing Mechanisms, fully described and represented in the following specification and the accompanying drawings, forming a part of the same.

10 The object of this invention is the superimposing of sheets of material in pairs, so that sheets following each other in succession may be brought together and be associated one upon another in proper register, and thus associated be operated upon or manipulated as a single sheet.

15 The invention is more especially designed to form part of or co-operate with the delivery mechanism of a printing-machine, wherein 20 sheets printed upon opposite surfaces or perfected follow each other in their travel to the delivery mechanism by which they are piled or folded, as the case may be; and the invention, though useful where flat delivery of the 25 sheets is to be effected, is particularly advantageous where sheets associated in pairs are to be folded together to form a single product, as an eight-page newspaper.

20 The invention consists in a superimposing mechanism composed of a single pathway, through which all of the sheets travel in the same course, and which is provided with a sheet-gripping mechanism located upon one side of the pathway, whereby one sheet is detained until a following sheet is brought into proper register therewith, and also with 35 means by which the advance end or head of said following sheet is directed past the rear end or tail of the detained sheet, so as to be 40 prevented from fouling therewith.

A practical embodiment of the invention as a part of the delivery mechanism of a printing-machine is illustrated by the accompanying drawings, in which—

45 Figure 1 is a plan view, and Fig. 2 a sectional elevation, of so much of the mechanism as is necessary to an understanding of the invention and its construction and operation. Enlarged views of the sheet-arresting mechanism are, however, given in Figs. 3, 4, and 5, 50 Fig. 3 showing the position of these parts

when one sheet has entered the mechanism and been arrested, Fig. 4 their position when two sheets have been entered, and Fig. 5 the position of the devices and the two superimposed sheets when the arrested one is released. 55 Figs. 6 and 7 illustrate the cam mechanism for operating the grippers, and Fig. 8 is a detail illustrating a modification which will be hereinafter referred to. Figs. 9 and 10 illustrate modifications of the superimposing apparatus, Fig. 9 showing, among other things, its combination with a vibrating folding mechanism, and Fig. 10 its combination with a rotary folding mechanism. 60 65

Before proceeding to a detailed description of its various devices, it is to be remarked that this sheet-superimposing mechanism may be successfully employed in connection with a printing-machine that has sheets fed to it by hand or automatically, or with a printing-machine that operates upon a web of material and separates the same into sheets by automatically-operating cutting devices; also that the sheets when associated or collected in pairs 70 may thereafter be folded by a folding mechanism that imparts a transverse or a longitudinal fold, or be delivered to a fly, or alternate pairs be delivered to different pathways to be conducted to separate delivery mechanism, 75 which may be fliers, folders, or associating mechanisms for combining some other product with said pairs of sheets. As, however, this superimposing mechanism is here illustrated as working in conjunction with a web-printing machine, and with a folding delivery that 80 imparts either a transverse fold or one on a line parallel with the travel of the sheets, the mechanism shown will be described with 85 particularity. 90

The cylinders A B at the left hand are illustrative of the cutting-cylinders of a perfecting-printing machine, between which cylinders the web of paper, when perfected by impressions on its opposite surfaces, is carried and severed or partially severed on transverse lines at such 95 distances apart (usually determined by the diameter of the cylinders) as to divide it at the "margin" into equalized sheets. These cylinders are provided with the usual cutting devices, a c, and will be geared with some of the rotating parts of the printing-machine, so as 100

to turn in unison with the printing-cylinders. From these cylinders A B the sheets pass into conducting-tapes 2 4, by which they are carried onward to the superimposing mechanism, said tapes running at such higher rate of speed than the cutting-cylinders as to cause each sheet as it is nipped by them to take up an accelerated movement, and thus be advanced rapidly enough to be separated from the following sheet, and thus provide an interval or working-space between each sheet and the following one; and if the web has been but partially severed this movement will also complete the severance. As here shown, these tapes 2 4 run out horizontally from the pulleys 20 21 for a distance something more than a sheet's length, and return horizontally over the parting-pulleys 22, and again pass out horizontally over pulleys 23. This makes a compact machine; but in some constructions the parting-pulleys 22 will be placed at such height relative to the cylinders A B as to cause said tapes to incline outward and upward.

The rotary carrier or cylinder C at the right is illustrative of the well-known rotary folding mechanism, which carrier is provided with a rotary folding-blade, 30, so geared and driven that during each revolution of the carrier C its edge will describe the epicycloidal path delineated by the dotted lines, and thus be protruded between the folding-rollers 31 32, and withdrawn therefrom in the manner and by means fully set forth in United States Patents No. 171,196, granted December 14, 1875, and No. 191,494, granted May 29, 1877. This carrier C may be provided with sheet seizing, holding, and releasing grippers 29, as in the first-named patent, or the same may be omitted, or pins may be used for controlling the leading edges of the superimposed sheets, as in Patent No. 143,674, granted October 14, 1873. The pulleys 20 21 are set some distance away from the cylinders A B, and the intervening space may be bridged, if desired, by conductors, as is common. The tapes 2 and 4, of which there are several in series, arranged in the same plane horizontally, as is shown in Fig. 1, constitute a pathway from the cutting-cylinders to the folding mechanism, but might be in more sections than one, if desired—that is, one section might terminate at the pulleys 23 and another extend from the pulleys 23 to the pulleys 32, and hence, as forming part of the superimposing mechanism, are only to be considered as extending from the entrance-point thereto to the source-supply of the sheets, or beyond the superimposing mechanism to the place of final delivery or further manipulation of the sheets. The tapes 2, as shown, extend from the pulleys 20 to and pass around the parting-pulleys 22, thence to and around the pulleys 23, thence to and around the carrier C, and thence return under stretching-pulleys 34 to the pulleys 20. The tapes 4 extend from the pulleys 27 to and pass around the parting-pulleys 22, thence to and around the pulleys 23 to the carrier C, on whose sur-

face they bear for a short distance, and thence pass around the folding-roller 32, and return over stretching-pulleys 33 to the pulleys 21. 70 These tapes are separated a slight distance at the pulleys 20 21, and have nipping contact at the parting-rollers 22, as is common, to effect the increased or accelerated movement of a sheet, whereby it is separated a distance from the following sheet to produce the interval or working-space between successive sheets. 75

Located between the pulleys 23 and the carrier C is the sheet arresting and retaining device and the means for directing the leading 80 end or head of the incoming sheet past the rear end or tail of the arrested sheet, which device and means co-operate with the single pathway formed by the tapes 2 4 to form the sheet superimposing or associating mechanism. This sheet arresting and retaining device, as shown, in the present case consists of a stop-bar, 5, and a set of co-operating grippers, 6. The stop-bar is located just in advance of the pulleys 23 and extends transversely of the machine with its ends supported upon the frame-work. As shown in Figs. 1 to 5, the bar lies between the tapes 2 4 and, in such position that the tapes 4, which pass above it, are raised and held a short distance away 90 from the tapes 2, and so that a small space is left between the bar and the latter tapes. The space thus provided affords room for the incoming sheet to pass forward beneath the bar without fouling with the rear end or tail of the arrested sheet. The grippers 6, which co-operate with the bar 5, consist of a number of separate members (see Fig. 1) all attached to a single rock-shaft, 7, that moves in bearings in the side frames, motion being communicated 105 to it to rock the grippers from the open position shown in Figs. 2 and 5 to the closed position shown in Figs. 3 and 4 by means of a rock-arm, 11, a connecting-rod, 12, and a lever, 13, that is vibrated at the proper intervals by a 110 cam or by other suitable means. Sheet after sheet passing in succession into the tapes 2 4, and the forward sheet separated a distance from the following sheet by the operation of the parting-pulleys 22, it results that as each 115 sheet is entered into the superimposing mechanism there will be an interval of time during which there is no sheet in the tapes between the stop-bar 5 and the pulley, 23, and that this will be greater or less according to the increased 120 surface-speed the tapes have over that of the cylinders A B. This interval produces a working-space between successive sheets, as hereinbefore described, through which the grippers 6 may operate. When the grippers 6 are 125 open or raised, as in Figs. 2 and 5, the sheet being carried forward over the pulleys 23 (call it the "first sheet 8") will lie upon the tapes 2 and pass outward under the stop-bar 5 toward the cylinder C. When, however, the tail of this sheet 8 is approaching the stop-bar 5, it will, if the grippers 6 are rocked in proper time to their closed position, (shown in Fig. 3,) have its tail engaged by said gripp-

pers and clamped onto the stop-bar 5, thus arresting the onward course of said sheet and detaining it for a suitable period to enable another sheet to pass onward beneath said first sheet 8. In this movement of the grippers 6 their ends will have described the path delineated by dotted lines in Fig. 5, and made their sweep through the tapes, but in the working-space existing between the sheet 8 and the next following sheet, and when they have completed such movement, as in Fig. 3, and clamped the sheet 8, they will then leave the pathway for the succeeding sheet clear and unobstructed. The second sheet (call it "9") carried forward over the pulleys 23 will likewise lie upon the tapes 2 and pass outward under the grippers 6, stop-bar 5, and the arrested sheet 8, as in Fig. 4, and when this sheet 9 has traveled forward far enough to bring its head or leading edge even with the leading edge of the sheet 8, thus superimposing the two sheets, the grippers 6 will be quickly opened to release sheet 8, as in Fig. 5, and said sheet will simultaneously take up an onward movement, and the two superimposed sheets will thereupon travel onward as a single sheet. As the leading end of the sheet 9 passes beneath the stop-bar 5, it will be guided past the rear end or tail of the arrested sheet by the grippers 6, so as to be prevented from fouling therewith. The reason for separating the tapes 2 and 4 by carrying the tapes 4 over the bar 5 will now be obvious, as will also the reason for bringing the tapes into nipping-contact at the carrier C, for it is apparent that sufficient space for the free travel of the sheets past the grippers 6 must be provided, and that some means for simultaneously starting the heads of the superimposed sheets forward will be required. The position of the bar 5 affords ample space for the passage of the sheets beneath the grippers, while the bringing of the tapes together upon the carrier gives them sufficient nip upon the sheets to start the sheet 8 as soon as it is released by the grippers. The means for causing the arrested sheet to start and move on with the moving sheet may, however, be made more positive by the provision of a drop-roller, 14, and its companion 15, as shown in Fig. 2, which rollers are driven by the tapes and of course with like surface-speed. The drop-roller 14 will be rocked into pressing contact with the superimposed sheets simultaneously, or nearly so, with the releasing movement of the grippers 6, and will be raised again at a suitable time not to obstruct or modify the arresting action of the grippers. No means is shown for operating the drop-roller, except its rock-arm 16, as they are common and well understood.

While the sheets will in practice follow or adhere to the tapes 2 in passing outward under the stop-bar 5, it may in manipulating some grades of paper be expedient to insure their passage beyond said stop-bar 5 without contact with the grippers, and hence, as shown in Fig. 4, only a number of conducting rods or bars

are illustrated as bridging the space between said stop-bar 5 and the pulleys 23. These conductors or rods 17 will be arranged in the spaces between the separate members composing the grippers 6, (see Fig. 1,) and starting rearward from the said stop-bar will extend to the pulleys 23, and their rear ends may, if desired, be curved to coincide with so much of the peripheral line of said pulleys as they cover. While any mechanism suitable for accomplishing that result may be employed to produce the vibratory movements of the grippers 6. Figs. 6 and 7 show one suitable for the purpose. This consists of a two-path cam-wheel, 40, one path, the groove 41, of which holds the lever 13 in such position as to cause the grippers 6 to stand open during one revolution of the wheel 40, while the other path, 85 its periphery 42, supports the lever 13 in such position as to cause the grippers 6 to remain closed during one revolution of the wheel 40; and the movement of the lever 13 from one path to the other at each revolution of the wheel 40 is effected by means of a switch, 43, that is pivoted in a recessed portion of the periphery of said wheel, and so shaped as to automatically present its points first in the position shown in Fig. 6, and then in that shown in Fig. 7. Assuming that the stud or friction-roller on the end of the lever 13 has, while the switch stands as in Fig. 6, passed from the periphery 42 of the wheel 40 underneath the switch and entered the path 41 to open the grippers 6, as there shown, it will be seen that as said wheel 40 continues to revolve in the direction of the arrow said roller will, as the heel of said switch passes it, throw the same into the position shown in Fig. 7, and hence that as the switch is again brought into contact with said roller (as a revolution of wheel 40 is accomplished) the roller will be forced to pass outward to the periphery of the wheel, thus closing the grippers 6, as in Fig. 7; 105 also, that as the wheel 40 continues to revolve said roller will again bear upon the heel of said switch, and, moving it in the opposite direction, throw the switch into the position shown in Fig. 6, to repeat the operation after 110 the wheel 40 has made another revolution during which it holds the grippers 6 closed. It is also to be remarked that the connections between the lever 13 and the gripper-shaft 7 may be of a different form from that shown. 120 For example, the rod 12, instead of being connected to an arm upon the gripper-shaft, may be provided with a rack which engages with a segment or pinion upon said shaft to effect the rocking of the same, as shown in Fig. 8. 125 It will of course be understood that the entrance-point to as well as the exit-point from the superimposing mechanism might each be between two sets of pulleys. Thus a set of pulleys located above the pulleys 23, and sets 130 like the pulleys 32 31, properly mounted to stretch the tapes 2 4 in a straight, preferably a horizontal, line, (see Fig. 9,) would serve the purpose. The tapes 2 might then return

from the pulleys 31 to the pulleys 23, and the tapes 4 from the pulleys 32 to the pulleys 60, resting on top or above the pulleys 23; or, if a set of pulleys, as 64, are used above the set 5 23, (see Fig. 9,) as carriers for the tapes 4, said pulleys may raise the tapes 4 but a slight distance, so that they do not bear upon the stop-bar 5, but bring the same outside or above the tapes 4, and this would render it 10 possible to have the tapes quite near together, if for any reason that should become desirable. These tapes might be long enough to lead the superimposed sheets over folding-rollers whose axes are parallel with the travel of the sheets, 15 and with which a suitable folding-blade is combined, so as to fold the superimposed sheets on a line parallel with their sides, which is shown in Fig. 9. Here the tapes 2 extend from pulleys 23 to the pulleys 31, and pass 20 over longitudinally-arranged folding-rollers 62, (only one of which is shown,) that are arranged as is common to co-operate with the vibrating folding-blade 61 placed above them. The tapes 4 extend from pulleys 64 to pulleys 32, said pulleys 64 being raised so as to 25 separate the tapes at the entrance-point. These tapes pass beneath the stop-bar 5, with which the grippers 6 co-operate, and have extending rearwardly from them guards or conductors 17, that terminate between the pulleys 23 30 60. Tapes *m* *n* are arranged to conduct the sheets from the cutting-cylinders B A to the superimposing mechanism, the tapes *m* in practice extending from the pulleys 21 to the pulleys 60, and the tapes *n* from the pulleys 20 to the pulleys 23, which tapes *m* *n* thus have a bend in passing over the pulleys 23, whereby a nip upon the sheets is insured, and as said pulleys 23 60 run at a higher speed 35 than the cutting-cylinders, the pulleys 23 will act as the parting-pulleys, in like manner as has been described with reference to pulleys 22, to provide a working-space between sheet and sheet. With the parts as shown in Fig. 40 9 the first sheet will obviously pass, supported by the tapes 2, outward under the conductor 17, and when its tail is passing the point occupied by the grippers 6 they will close and seize the tail of the sheet, clamp it 45 against the bar 5, and thus arrest its progress. The following sheet will be carried onward in the same pathway, which, (from the closed position of the grippers shown in Fig. 10,) it 50 will be observed, is entirely unobstructed, and when it has reached the position of coincidence with the first sheet the latter will be released by the grippers, and simultaneously, or nearly so, with such releasing the drop-roller 14 will descend to bear the tapes 55 60 4 into nipping contact with the two superimposed sheets, which, thereupon, will take up a like onward movement, and together be carried outward over the folding-rollers 62, and when they have reached a proper position with 65 reference to said rollers the folding-blade 61 will be vibrated to fold the two superimposed sheets as one into the nip of said rollers, which,

revolving, will deliver the same folded longitudinally.

It is not essential that the single pathway of this superimposing apparatus shall be composed of tapes, or that the sheet arresting and retaining mechanism and the guides or conductors 17 should be located above it. Indeed, it is practicable to have it made up of 70 bars entirely, if suitable driving-pulleys never more than a sheet's length distant from each other are employed. It is also practicable to use one set or series of carrying-tapes, and form the other side of the pathway of bars 80 like 71, (shown in Fig. 10,) which bars, it will be observed, supplant the tapes 4 and their pulleys 64 so far as said tapes have formed the upper member of the superimposing pathway. In said figure the tapes 2 run from 85 the pulleys 20 over the parting-pulleys 23 and return around the folding-cylinder C and stretching-pulleys 34, and the tapes *m* are retained as in Fig. 9. In this arrangement the tapes 4 are, however, returned from the pulleys 90 32 around the drop-roller 14, and the parting-roller 15 is also omitted, as the stretch of the tapes over the carrier C is sufficient to nip the sheets.

The construction and arrangement of the 95 stop-bar 5, conductor 17, and gripper 6 are the same as in Fig. 9, and the bars 71 are supported at their rear ends as projections from the stop-bar 5 and at their front ends by a cross-bar. In this arrangement the first sheet 100 passes onward in the pathway until arrested, as before described, by the closing operation of the grippers 6, and the second sheet passes onward in the unobstructed pathway until it arrives underneath the first sheet, in coincidence therewith, whereupon the grippers release the first sheet, and the drop-roller 14 descends to cause the heads of both superimposed sheets to be nipped, and said sheets to 105 be carried onto the carrier C, and thereafter 110 to be transversely folded through the pulleys 115 31 32.

The arrangement of the stop-bar 5 in Figs. 9 and 10 is specially desirable, since it affords 120 so much greater space than is required for the passage of the sheets as to enable the first or arrested one to be raised a considerable distance, and thus provide more than the actual space needed for the second sheet to travel in, thus preventing contact of the two sheets, and thereby avoiding any smutting by their rubbing against each other; and this arrangement 125 also admits of the application to the first sheet of a longitudinally central line of paste, whereby the two sheets may be cemented together on the line of their fold when that fold is a longitudinal one. This may be done by a pasting apparatus operated like that shown in the patent numbered 195,115, granted September 11, 1877, arranged to work in connection 130 with a pulley on the shaft of pulleys 23. The bars 71 17, instead of taking the place of the tapes 4, may take the place of the tapes 2, and the bar 5 and the grippers 6 may in any case

be arranged below instead of above the pathway.

From the foregoing it will be seen that the essential features of this invention are a single channel or pathway in which all of the sheets take the same course, as distinguished from two channels or pathways into which the sheets are alternately directed by a switch or some equivalent device, and a sheet arresting and retaining device arranged to act upon the rear end or tail of the sheet and located outside the pathway or in such position that one sheet of a line or series may be arrested and detained by said mechanism without either interfering with the passage of the following sheet through the same pathway.

It will sometimes occur, where an inferior grade of paper is used, that the arrested sheet, when released, will not promptly take up the movement of the tape so as to accomplish and preserve the register with its moving companion which this superimposing mechanism is designed to effect. I therefore have devised a duplex arresting mechanism that consists of a double set of grippers, one set, 6, acting as herein described, and a second set coacting therewith, so as to come into operation in time to arrest the second sheet, and these open simultaneously with the grippers 6, whereby the same conditions are imposed upon each of the superimposed sheets—namely, each is arrested, and both are simultaneously released, and each is compelled to take up its movement under the same conditions and by the same means, and hence the register once secured will be maintained. This improvement will, however, constitute the subject-matter of another application.

40 What is here claimed is—

1. The combination, with means forming a pathway for the passage of a line or series of sheets and means for advancing the sheets therein so that all take the same course in the pathway, of a gripping mechanism located upon one side of the pathway and arranged to grasp and retain one sheet until the next following sheet is in register therewith and to then release the detained sheet so that the two can pass forward together, all substantially as described.

2. The combination, with means forming a single pathway for the passage of a line or series of sheets and means for advancing the sheets therein so that all take the same course in the pathway, of a sheet-arresting mechanism located outside the pathway and arranged

to act upon the rear end or tail of the sheet, to arrest and detain one sheet until the following sheet has been advanced so as to be in register therewith, and means, as the conductors 17, for directing the advance end or head of said following sheet past the rear end or tail of the arrested sheet, all substantially as described. 50

3. The combination, with means forming a pathway for the passage of a line or series of sheets and means for advancing the sheets therein, of the stop-bar 5, arranged upon one side of said pathway so that all of the sheets pass upon the same side of the bar, and the grippers 6, arranged to grasp one sheet and retain it until the next following sheet is in register therewith, all substantially as described. 65

4. The combination, with means forming a pathway for the passage of a line or series of sheets and means for advancing the sheets therein so that all take the same course in the pathway, of a gripping mechanism located upon one side of the pathway, and arranged to grasp and retain one sheet until the next following sheet is in register therewith, and to then release the detained sheet so that the two can pass forward together, and the drop-roller 14, for causing the superimposed sheets to start forward promptly, all substantially as 75 described. 80

5. A sheet-superimposing mechanism consisting of two series of moving tapes, as 24, between which are conveyed a line or series of sheets, a stop-bar, as 5, upon one side of 90 which all of the sheets are caused to pass, and a set of sheet-grippers, as 6, which are operated to grasp and retain one sheet until the following sheet is in register therewith, all substantially as described. 95

6. The combination, with means forming a pathway for the passage of a line or series of sheets, and means for advancing the sheets therein so that all take the same course, of the grippers 6 and co-operating stop-bar 5, 100 said bar being sufficiently removed from one side of said pathway to permit the grippers to carry and hold the rear end of the arrested sheet out of the way of the head of the incoming sheet, and conductors, as 17, projecting 105 into the pathway beyond the nipping-face of the stop-bar, all substantially as described.

In testimony whereof I have hereunto set my hand in the presence of two subscribing witnesses.
